(57) **CLAIM**

The ornamental design for a light kit set as shown and described.

DESCRIPTION

FIG. 1 is a front, left and top perspective view of a light kit set, showing my design.

FIG. 2 is a front, left and top perspective view of a first portion of the light kit set of FIG. 1.

FIG. 3 is a rear, right and bottom perspective view of FIG. 2.

FIG. 4 is a front elevation view of FIG. 2.

FIG. 5 is a rear elevation view of FIG. 2.

FIG. 6 is a left side elevation view of FIG. 2.

FIG. 7 is a right side elevation view of FIG. 2.

FIG. 8 is a top plan view of FIG. 2.

FIG. 9 is a bottom plan view of FIG. 2.

FIG. 10 is an enlarged view of detail 10 in FIG. 2.

FIG. 11 is a front, left and top perspective view of a second portion of the light kit set of FIG. 1.

FIG. 12 is a rear, right and bottom perspective view of FIG. 11.

FIG. 13 is a front elevation view of FIG. 11.

FIG. 14 is a rear elevation view of FIG. 11.

FIG. 15 is a left side elevation view of FIG. 11.

FIG. 16 is a right side elevation view of FIG. 11.

FIG. 17 is a top plan view of FIG. 11.

FIG. 18 is a bottom plan view of FIG. 11.

FIG. 19 is an enlarged view of detail 19 in FIG. 11.

FIG. 20 is a front, left and top perspective view of a third portion of the light kit set of FIG. 1.

FIG. 21 is a rear, right and bottom perspective view of FIG. 20.

FIG. 22 is a front elevation view of FIG. 20.

FIG. 23 is a rear elevation view of FIG. 20.

FIG. 24 is a left side elevation view of FIG. 20.

FIG. 25 is a right side elevation view of FIG. 20.

FIG. 26 is a top plan view of FIG. 20.

FIG. 27 is a bottom plan view of FIG. 20.

FIG. 28 is an enlarged view of detail 28 in FIG. 20.

FIG. 29 is a front, left and top perspective view of a fourth portion of the light kit set of FIG. 1.

FIG. 30 is a rear, right and bottom perspective view of FIG. 29.

FIG. 31 is a front elevation view of FIG. 29.

FIG. 32 is a rear elevation view of FIG. 29.

(Continued)

FIG. 33 is a left side elevation view of FIG. 29.
 FIG. 34 is a right side elevation view of FIG. 29.
 FIG. 35 is an enlarged top plan view of FIG. 29.
 FIG. 36 is an enlarged bottom plan view of FIG. 29.
 FIG. 37 is an enlarged view of detail 37 in FIG. 29.
 FIG. 38 is a front, left and top perspective view of a fifth portion of the light kit set of FIG. 1.
 FIG. 39 is a rear, right and bottom perspective view of FIG. 38.
 FIG. 40 is a front elevation view of FIG. 38.
 FIG. 41 is a rear elevation view of FIG. 38.
 FIG. 42 is a left side elevation view of FIG. 38.
 FIG. 43 is a right side elevation view of FIG. 38.
 FIG. 44 is a top plan view of FIG. 38.
 FIG. 45 is a bottom plan view of FIG. 38.
 FIG. 46 is an enlarged view of detail 46 in FIG. 38; and, FIG. 47 is another front, left and top perspective view of the light kit set in a usable state of FIG. 1.
 The dashed broken lines depict portions of the light kit set that form no part of the claimed design.
 The dot-dash broken lines in FIGS. 2, 10, 11, 19, 20, 28, 29, 37, 38 and 46 depict the boundaries of the enlargements and form no part of the claimed design.

1 Claim, 47 Drawing Sheets
